UNITED STATES PATENT OFFICE

158,748

WATERPROOF CARRYING BAG

Lee C. Hosfield, Bennington, Vt., assignor, by
mesne assignments, to Dan Holland Co., Inc.,
Washington, D. C., a corporation of Delaware

Application April 8, 1948, Serial No. 145,590

Term of patent 14 years

(Cl. D87—5)

To all whom it may concern:

Be it known that I, Lee C. Hosfield, a citizen of the United States of America, residing at Bennington, in the county of Bennington and State of Vermont, have invented a new, original, and ornamental Design for a Waterproof Carrying Bag, of which the following is a specification, reference being had to the accompanying drawing, forming part thereof.

In the drawing:

Figure 1 is a view of one side of a waterproof carrying bag showing my new design;

Figure 2 is an end view thereof; and

Figure 3 is a view similar to Figure 1 showing the opposite side of the waterproof carrying bag.

I claim:

The ornamental design for a waterproof carrying bag, as shown.

LEE C. HOSFIELD.
